UNITED STATES PATENT OFFICE.

JOHN NUSSER, OF MALLANAUR, PENNSYLVANIA.

ADJUSTABLE SUPPORT FOR EMBROIDERY-HOOPS.

1,171,871.

Specification of Letters Patent. Patented Feb. 15, 1916.

Application filed March 12, 1915. Serial No. 13,865.

To all whom it may concern.

Be it known that I, JOHN NUSSER, a subject of the King of Hungary, residing at Mallanaur, in the county of Allegheny and State of Pennsylvania, have invented 5 certain new and useful Improvements in Adjustable Supports for Embroidery-Hoops, of which the following is a specification.

10 This invention relates to an adjustable support for embroidery hoops and has for its object to provide a support of such type, in a manner as hereinafter set forth, for the purpose of connecting the hoops to a stationary object and to further enable the hoops 15 when connected to be adjusted to various angles with respect to the support.

Further objects of the invention are to provide a support for the purpose set forth 20 which is simple in its construction and arrangement, strong, durable, efficient and convenient in its use, readily set up with respect to the hoop, and inexpensive.

With the foregoing and other objects in 25 view the invention consists of the novel construction, combination and arrangement of parts as hereinafter more specifically described and illustrated in the accompanying drawings wherein is shown an embodiment 30 of the invention, but it is to be understood that changes, variations and modifications can be resorted to which come within the scope of the claims hereunto appended.

In the drawings wherein like reference 35 characters denote corresponding parts throughout the several views:—Figure 1 is a sectional elevation of an embroidery hoop support in accordance with this invention showing the adaptation thereof in connection with the hoops. Fig. 2 is a top plan view. Fig. 3 is a sectional detail.

Referring to the drawings in detail 1 denotes a table top or other stationary object and to which the support, in accordance 40 with this invention, is adapted to be detachably clamped.

The support comprises a U-shaped body portion 2 and the arms of the latter are indicated at 3, 4. The arm 3 projects at its 45 free end in the head 5 of a length greater than the width of said arm 3 and the said head 5 is disposed centrally with respect to the upper end of said arm 3. One face of the head 5 is flat and its other face arcuate 50 as indicated at 7. The arm 4 has its free end provided with a circular head 8 formed with

a centrally disposed body opening 10 and said head 8 is arranged parallel to the head 5. The heads 8, 5, are disposed at right angles with respect to the direction of the length of the arms 3, 4.

Depending from the body portion 2 is an angle-shaped member 11, which has its free terminus of the horizontal leg thereof provided with a circular enlargement 12 disposed at right angles with respect to the heads 5, 8, and formed with a screw threaded opening 13. Extending from one end of the body portion 2 is a projection 14, which terminates in a circular enlargement 15 arranged parallel with the enlargement 12.

Extending up through the circular enlargement 12 and engaging with the ends of the threaded opening 13 is a clamping screw 16, having its lower end provided with a thumb piece 17, and its upper end with a disk 18, the latter being swivelly connected to the said upper end of the screw 16.

The arm 11, enlargement 12, screw 16, disk 18, projection 14 and enlargement 15 30 constitute a clamp for detachably connecting the body portion 2 of the support to the table top 1.

Adjustably engaging in the head 8 is a clamping screw 19, having one end provided 35 with a thumb piece 20 and its other end with a curved clamping head 21 having its top, at each side, formed with a forwardly projecting flange 22. The head 21 is of a length greater than the diameter of the screw 19 40 and the head 21 is adapted to be positioned against the periphery of the outer hoop 23, of a pair of hoops, and oppose the head 5, the latter being positioned against the inner face of the inner hoop 24 of the pair 45 of hoops. When the screw 19 is adjusted, the heads 8 and 21 clamp the hoops with the body portion 2 and when the hoops are clamped in a manner just stated the flanges 22 extend over the edges of the hoops 23 50 and 24 for the purpose of maintaining them in alignment.

The clamping head 21 is swivelly connected to the clamping screw 19 as at 24 and by such an arrangement hoops can be positioned at any desired angle with respect to the body portion 2.

The reference character 25 denotes a piece of fabric which is clamped in position by the hoops 22 and 23.

What I claim is:—

1. A device for the purpose set forth com-

prising a U-shaped body portion having the free end of each of its arms provided with a head, one of said heads having an arcuate face and the other of said heads formed with a threaded opening, a clamping screw extending through and engaging with the wall of said opening, a curved head swivelly mounted upon one end of said screw and associating with said imperforate head for clamping a fabric supporting member with said body portion, said swiveled head permitting of the angular adjustment of said member with respect to said screw, a pair of flanges projecting forwardly from the top of said swiveled head and capable of overlapping said member, means carried by the body portion for detachably clamping it to a support.

2. A device for the purpose set forth comprising a U-shaped body portion having the free end of each of its arms provided with a head, one of said heads having an arcuate face and the other of said heads formed with a threaded opening, a clamping screw ex-

tending through and engaging with the wall of said opening, a curved head swivelly mounted upon one end of said screw and associating with said imperforate head for clamping a fabric supporting member with said body portion, said swiveled head permitting of the angular adjustment of said member with respect to said screw, a pair of flanges projecting forwardly from the top of said swiveled head and capable of overlapping said member, a lateral projection carried by the bottom of said body portion, an angular-shaped arm depending from the bottom of said body portion, and means carried by said angular-shaped arm and associated with said projection for detachably clamping said body portion to a support.

In testimony whereof I affix my signature in presence of two witnesses.

JOHN NUSSER.
